UNITED STATES PATENT OFFICE.

EDWARD C. KAHN, OF MILWAUKEE, WISCONSIN.

FLUID-FUEL BURNER.

1,265,210.

Specification of Letters Patent. Patented May 7, 1918.

Application filed October 27, 1916. Serial No. 128,013.

To all whom it may concern:

Be it known that I, EDWARD C. KAHN, a citizen of the United States, and resident of Milwaukee, in the county of Milwaukee and State of Wisconsin, have invented certain new and useful Improvements in Fluid-Fuel Burners; and I do hereby declare that the following is a full, clear, and exact description thereof.

10 The present invention relates to new and useful improvements in liquid fuel burners and is more particularly directed to the provision of an improved generator structure adapted for use preferably in connection 15 with the type of liquid fuel burner head embodied in my previous application for patent executed November 19, 1915, and filed Oct. 27, 1916, Serial No. 128006.

One important object of the present invention is to provide a generator so formed with relation to the burner that a proper heating to procure vaporization of the fuel is had at all times, and wherein the danger of overheating and consequent liability of 25 melting or otherwise injuring the generator by operation of the burner at a relatively great heat is prevented.

Another important object resides in the provision of a generator and burner head 30 so relatively arranged and connected as to form a compact structure adapted to be supported entirely by a supply pipe member whereby the device is particularly adapted for use in connection with single head burners of the type including a reservoir base member and a supply pipe stand projecting therefrom.

A further object resides in the provision 40 of a structure as above described wherein the parts are securely held in proper relative position for efficient operation, and wherein all of the parts may be readily disassembled for cleaning.

It is also an object in connection with the 45 generator to provide a chamber wherein deposits of carbon given off by vaporization of the fuel will be collected for ready removal.

With the above and other objects in view 50 the invention resides more particularly in the novel combination, arrangement and formation of parts more particularly herein-after described and particularly pointed out in the appended claims.

55 In the drawings.

Figure 1 is a vertical sectional view taken

through the improved structure, the line 1—1 of Fig. 2 indicating the plane on which the section is taken, and showing the burner head in elevation.

60 Fig. 2 is a side view of the generator structure with a portion thereof broken away to disclose the collection pocket.

Referring now more particularly to the accompanying drawings, 5 designates the 65 supply head which forms the body of the improved generator and burner head carrying structure, this supply head comprising a cylindrical member provided adjacent its upper end with lateral branches 6 and 7 and 70 adapted to threadedly engage at its lower end in a supply pipe 8 which forms the support for the entire structure. This supply pipe would in some instances project upwardly from a suitable reservoir base (not shown) 75 whereby the entire burner would comprise a unitary structure.

Above the branches an annular shoulder 9 is formed on the head which seats the bight of a spider member 10, the legs of 80 which extend upwardly in divergent relation and are offset at their end portions to form seating ledges 11 for the burner head A, this burner head being preferably of the type disclosed in my application for 85 patent filed Oct. 27, 1916, although other types of burner heads including annular series of openings could be employed. The legs 10 of the spider member are preferably 90 V-shaped in cross-section to procure proper strength, as the spider member is preferably stamped from a single sheet of material, and the spider member is securely held on the head 5 by a follower nut 12 threaded on the upper end of the head 5.

95 The generator comprises a tubular ring 13 provided at diametrically opposed portions with depending tubular sections 14 and 15 respectively which are connected each by suitable union couplings 16 to pipe sections 17 which are converged inwardly and threadedly engaged in the branches 6 and 7 respectively of the supply head whereby the generator is held spaced above the lower portion of the burner head in such relative 105 elevation that its axial plane is disposed slightly below the plane of the lowermost series of the jet apertures 18 of the burner head. The unions 16 are preferably of a general type including sleeve members having 110 rotative engagement with the pipes 17 and threaded engagement with the rest sec-

tions 14 and 15 of the generator whereby ready assembly of the structure is facilitated. While the generator has been described as an annular ring with pipes connected thereto, it may more generally be termed as a tube member which extends upwardly from the supply head and is branched to embrace the burner and then extends downwardly to the supply head, this being in effect the structure procured.

10 The supply head is provided with a longitudinal passage 19 which extends from its bottom through the branch 6 to provide communication between the supply pipe 8 and the pipe 17 of the section 14, and the head is also provided with a passage 26 extending through the branch 7 and directed longitudinally through the upper portion of the head to provide communication between the other pipe 17 and a nozzle member 21 threaded in the upper end of the supply head to discharge into the mixing tube 22 of the burner head.

15 Thus in operation the fluid passes through the supply head and a respective pipe 17 to the section 14 from whence it branches to extend through the generator body at both sides of the burner head A, said branches meeting at and passing through the section 15 and the other pipe 17 back to the supply head and outwardly into the burner head through the nozzle 21. The sides of the generator section 14 are flared toward the generator body whereby a pocket is formed 25 at the entrance of the fluid to the generator, and this pocket serves to collect any carbon given off by the fluid upon vaporization thereof, it being noted that the carbon is only given off at the moment of vaporization. In operation the fluid in rushing into the pocket would be vaporized, and before passing through the generator a churning action would be procured in the pocket to deposit on the walls thereof, any carbon or 40 other solid formed at the moment of vaporization. The fluid in vaporized state passes then through the generator ring to be further heated to procure a proper degree of heat and pressure.

45 50 By extending the generator entirely around the burner a less application of heat to the generator is necessary to procure proper operation than if the generator extended only partially around the burner and by forming the generator in a ring having depending sections, the entire periphery of the burner is utilized for heating and a two-point support is procured for the generator, which is held free for the proper action of the flames of the burner head thereon. It has been stated that the axial plane of the generator ring is slightly below the lower ring of openings 18 of the burner head. Thus when the burner is operating 55 at a comparatively low pressure, the flames,

in striking the generator ring, are extended thereunder to practically envelop the ring. When, however, the burner is operating at a high pressure the flames will be more readily deflected upwardly and consequently 70 although a greater heat will be applied at the upper portion of the ring, a less heat will be applied at the lower portion of the ring, and the generator will receive a proper amount of heat at whatever pressure the 75 burner is operated. As different grades of fuel produce different pressure and heating conditions, the present structure is efficiently operable under varying conditions and with various fuels without the necessity of providing discharge nipples of different sizes and types to meet various conditions such as would otherwise be the case.

80 The pocket 23 receives a relatively great amount of heat due to action thereon of the 85 flames which would otherwise pass under the generator ring, and this heat materially aids in procuring the initial vaporization of fuel in the pocket.

85 For procuring an initial heating of the 90 generator to start operation of the burner, a cup shaped member 24 is threaded on the supply head below the branches and substantially semicircular troughs 25 are disposed below the generator ring and are supported 95 in such position by bosses 26 depending from intermediate portions of the ring and receiving screw 27 passed through said troughs, these troughs and the cup shaped member being adapted to receive suitable 100 combustible fluid.

I claim:

1. The combination with a burner head, of an annular generator chamber surrounding the burner head, a pair of tubes extending downwardly from the chamber, a supply head having a pair of passages formed therein and communicating with said tubes, a discharge nozzle communicating with one of said passages, a fuel supply communicating 105 with the other of said passages, and a collector pocket formed in the generator chamber at the juncture of the tube communicating with the supply passage and said chamber.

110 115 2. In a burner, a supply head, a spider carried by the supply head with its legs projected upwardly therefrom, a burner head carried by said legs, pipes extending outwardly and upwardly from said supply head, an annular generator chamber carried by said pipes and communicating therewith and inlet and outlet passages respectively formed in the supply head for said pipe ends.

120 125 3. In a burner, a supply head, an annular generator carried by the supply head, a discharge nozzle carried on the upper end of the supply head, a spider member having its right portion secured on the head with its 130

arms extending upwardly and a burner head carried by said arms, said annular generator surrounding the burner head, substantially as described.

5 4. In a hydro-carbon burner, a supply head having outwardly and upwardly extending passages therein, a spider member having its bight secured to the supply head, a burner head carried by the spider member, a generator chamber surrounding the burner head, pipes connecting the generator chamber with the passages in said supply head, a nozzle in the top of said supply head and in communication with one of the passages therein, and a supply pipe leading to the bottom of the supply head and communicating with the other of said passages.

10 5. In a hydro-carbon burner, a supply head comprising an upwardly extending arm, a downwardly extending arm and a pair of outwardly and upwardly extending arms, passages through said supply head,

one of said passages passing through the downwardly extending arm and one of said outwardly and upwardly extending arms, 25 and the other passage passing through the two other of said arms, a burner head disposed above said supply head, a generator chamber surrounding said head and supported by pipes communicating therewith 30 and with said upwardly and outwardly extending arms of the supply head, a nozzle in the upper arm of said supply head and communicating with the burner head, and a supply pipe connected with the lowermost 35 arm of said supply head substantially as described.

In testimony that I claim the foregoing I have hereunto set my hand at Milwaukee, in the county of Milwaukee and State of 40 Wisconsin, in the presence of one witness.

EDWARD C. KAHN.
